METHOD OF DESTROYING SEWAGE

Henry H. Moreton, Santa Monica, Calif.

Application August 2, 1935, Serial No. 34,481

8 Claims. (Cl. 110—14)

This invention is a method and apparatus for effecting complete destruction of sewage.

The effective destruction of sewage without soil or water pollution has long been a serious problem. In fact, attempts heretofore made to physically destroy sewage have met with indifferent success from the standpoint of practical economy, and convenience and complete sanitary safety in handling, and so that at the present time, the so-called bacterial systems are considered the safest and most desirable methods for municipal installations. A system of the last-mentioned type, however, involves the installation of apparatus which must be spread over a considerable area, requires a very large investment to meet the initial cost of installation, and is more or less expensive to operate.

One of the objects of the invention is to provide for complete and economical physical destruction of sewage by incineration, whereby practically no residue is left, so that the possibility of either soil or water pollution is reduced to the absolute minimum. A further object is to provide for complete incineration of sewage in such manner that the discharge of objectionable and offensive odors, smokes and gases into the surrounding atmosphere is prevented. A further object is to provide a system of low installation cost and highly economic operation, capable of providing for initial dehydration of the sewage and subsequent complete incineration in a continuous process. A further object is to employ the calorific values inherent to the sewage being treated, to assist in the incineration of the material being treated, after its dehydration.

The invention will be hereinafter fully set forth and particularly pointed out in the claims.

In the accompanying drawings:

Figure 1 is a vertical elevation more or less diagrammatic in character, illustrating an apparatus constructed in accordance with the invention, certain parts being shown in section. Figure 2 is a detail sectional view of a portion of one of the rotatable furnaces. Figure 3 is a side elevation diagrammatically illustrating a modification.

Referring to the drawings, I designate a combined dehydrator and incinerator, which consists of a relatively long cylindrical chamber 10, rotatably supported in a longitudinally inclined position, in a well known manner, by suitable bearings 11. Rotation of the cylindrical chamber may be effected by any suitable means, such as a gear 12 engaging a gear-ring 13, which encircles 50 the chamber 10. The higher end of said chamber

10 projects into a receiving chamber 14, through the top of which extends an inlet chute 16.

The open lower end of the cylindrical chamber 10 extends into a burner box 20, into which is projected one or more burners 21 for gas, oil, or the like, the delivery ends of the burners being directed axially toward the incinerator I, in such manner as to project the flame into the open lower end of the latter. The burner casing rests 10 upon a suitable platform 22, onto which the chamber 10 deposits the material which is discharged from the lower end thereof, said platform having a chute 23 which communicates with the interior of a mixing apparatus 24, operated by a suitable motor 25. The mixing apparatus 24 may be of any suitable or desired construction, such as the common type of apparatus usually employed for mixing concrete. Any gases which may accumulate in the top of the 20 mixer are drawn out by blower 15 and delivered to the burner box 20. A flue 26 connects the receiving chamber with an offset chamber a of a stack S.

The mixer 24 discharges into the inlet chute 25 16a, located within a receiving chamber 14a, of a second incinerator I', which is in every particular a duplicate of the incinerator I, except that it is inclined in the opposite direction. That is, said incinerator I' consists of a relatively long cylindrical chamber 12a, which is rotatably supported in a longitudinally inclined position, by suitable bearings 11a. Rotation of said cylinder 10a may be also effected by means of a gear 12a engaging the gear-ring 13a, encircling the cylinder 10a. A 35 flue 26a connects the receiving chamber 14a with offset chamber a' of the stack S. The incinerator I', at its lower end, discharges into a burner box 20a, into which is projected one or more burners 21a, similar to the burners 21, the delivery ends of the burners being directed axially toward the incinerator I', in such manner as to project the flame into the open lower end of the latter. The burner casing 21a also rests upon a suitable platform 22a, onto which said chamber 40 45 I' discharges the material which has been passed therethrough, said platform also having a chute 23a, which discharges into a second mixer 24a, similar in every respect to the mixer 24, and driven by a motor 25a, and similarly vented by 50 blower 15a.

The mixer 24a may discharge into a suitable storage bin or the like, but it is preferred to discharge the same into the bottom of a conveyor pit 27, from which a chain conveyor 28 will de- 55

liver the discharged material to an elevated distributing chamber 28', adjacent the high end of incinerator I, from which material may be fed to the last-mentioned incinerator through the inlet 5 chute 16. It will be observed that each of the incinerators I and I' is provided with an annular baffle 29, which is spaced a short distance from the delivery end of the chamber.

Located in a suitable position adjacent to the 10 apparatus thus far described is a suitable storage tank 30 for the sewage, preferably in the form of sludge. Leading from the lower end of said tank is a discharge pipe 31, which delivers the sludge to the pump 32, by which the sludge is delivered to the mixer 24 through a pipe 33. Also 15 leading from the tank 30 is a branch outlet pipe 31a connected to a second pump 32a, which delivers sludge through a pipe 33a to the mixer 24a. The pumps 32 and 32a are driven in suitable 20 manner, as by a motor 34.

In operation, assuming the burners 21 and 21a are lighted and in operation, an initial charge of sand or similar inorganic granular material, capable of withstanding high temperature without 25 fusing, is placed in the pit 27. It is preferred to use good sharp silica sand. Sufficient sand must be initially employed to insure a continuous stream of sand through all of the incinerators. The sand is elevated to the hopper 28' and introduced 30 into the incinerator I through the chute 16, and the rotation of the cylinder 10 will cause the sand to travel slowly downwardly through said cylinder, so that it will receive a high temperature due to the heat generated by the burners 21. The burners are directed toward the 35 downwardly flowing material in a manner adapted to impart a relatively high temperature to the sand, but the heat must be regulated so as to avoid fusing temperature, because fusing of the sand particles would greatly impair the operation.

The apparatus will be primed for operation at the time that cylinder 10 begins to discharge heated sand from the lower end thereof. As the heated sand is discharged from the incinerator I, it is delivered to the mixer 24. Coincidentally with delivery of hot sand to the mixer, the pump 32 is put into operation, so as to deliver sludge to the mixer 24 for mixture with the heated sand. The sand and sludge are intimately 45 mixed until the sand particles are thoroughly coated with colloidal portions of the sewage constituents. The coated inorganic material is then discharged into the high end of incinerator I'. Because of the rotation of the chamber 10a the 50 coated material will be tumbled about and agitated, and caused to travel downwardly toward the burners 21a, thereby being caused to move through a heated space within which it is subjected to a gradually increasing temperature as 55 it approaches said burners. Therefore, almost immediately after the mixture enters the incinerator I', the temperature is sufficiently high to dehydrate the coatings, and during the subsequent travel of the mixture the temperature is 60 sufficiently increased to ignite the dehydrated organic material, but without fusing the refractory material, and incineration of the organic constituent is completed by the time that the granular carrier material reaches the discharge 65 end of said chamber 10a and immediately before it is discharged into the mixer 24a. Due to the retarding action of the baffle 29, a constantly moving bed of fire back of the baffle is provided, with the result that complete combustion takes 70 place in this zone, to such an extent that there is 75

practically no residual matter left by the sewage, and the material discharged to the mixer 24a is practically the dried heated sand. As dehydration and incineration take place during the travel of the mixture, combustible gases are given off, 5 which are ignited by the heat within the cylinder, thereby aiding in the combustion of the dehydrated coatings material. The products of combustion pass to the stack S through flue 26.

As the stream of sand is discharged from 10 chamber 10a, it is delivered to the mixer 24a, and at this time the pump 32a is put into operation, so as to supply sludge to the mixer 24a, as the latter receives the hot sand from said chamber 10a. Said sand and the new sludge are intimately mixed and the sewage-coated refractory material is discharged into the pit 27. From this last position, the mixture of hot sand and sludge is elevated to the platform 28 and discharged into the incinerator I through the chute 16, whereupon the mixture travels through the chamber 10 in such manner as to be subjected to the heat of the burners 21, so that dehydration takes place at the upper portion, and complete combustion takes place at the baffle 29, in the manner already described in connection with the incinerator I', the products of combustion passing to the stack through chamber 16. In both instances the operation is so complete that as dehydration takes place, the combustible gases will also be ignited, 30 thereby materially aiding in the destruction of odors and smoke, as well as in the combustion of the sewage itself, the gases of combustion which are carried to the stack being without noticeable odor. From the foregoing, it will be observed that once the apparatus has been put into operation, the cycle is continuous and that the same batch of sand may be used over and over indefinitely as long as the heat is kept below the fusing temperature. If desired, however, at the 40 end of a cycle the sand that has been used may be replaced with new sand, the old sand being treated to a separating process of any desirable character, so as to remove any foreign material which may possibly remain, so that the sand is 45 rendered sufficiently pure for building purposes.

Where a plant of smaller capacity will suffice, a single incinerator I² may be employed in lieu of the plurality of incinerators illustrated in Figure 1. Such a modification is illustrated in Figure 3, in which the same type of rotating cylinder 10b is employed, as heretofore described, the same being provided with the receiving chamber 14b, the burner chamber 20b and burners 21b, rotation of the cylinder being effected in the 55 manner already described in connection with Figure 1. Material from the chamber 10b is discharged into a mixer 24b, which is vented by means of the blower 15b, and the mixture discharges through a spout 37 onto a conveyor C, 60 which elevates the mixture to the chute 16b, so as to be delivered into the chamber 14b. Sludge is supplied to the mixer through the pipe 33b. The receiving chamber 14b is connected with an extension a² of the stack S by means of a flue 26b. 65

In operation of the form disclosed in Figure 3, a charge of sand is first introduced through the chute 16b into chamber 10b, and is heated by the burners as it travels toward the lower end of said chamber. The hot sand is then discharged 70 into the mixer 24b and mixed with sewage sludge in the manner already fully described, and the mixture is deposited upon the conveyor, so that it will be elevated and discharged into the chute 16b. Thereafter, the mixed sludge and hot sand 75.

will travel through the cylinder 10b, and during this travel the sludge will first be dehydrated and then completely incinerated, so that the practically pure heated sand may again be discharged into the conveyor for another cycle. The foregoing cycle may be continued until the supply of sludge is exhausted.

As previously stated, any preferred type of mixer may be employed in the apparatus illustrated in the drawings, but in each instance it is preferred to provide a structure similar to that shown in Figure 3, in which a baffle 35 depends from the top wall of the mixer to a position well below the normal liquid level in the mixture, so as to trap any gases and to allow them to escape into the upper part of the mixer, where they are vented in the manner already described. The mixture is forced outwardly from the mixer through the outlet opening 36 into the discharge spout 37.

The advantages of the invention will be readily apparent to those skilled in the art to which it belongs. An important advantage is that owing to the fact that the sand particles acquire coatings of the colloidal constituents of the water content of the sludge during the passage of the mixture through the incinerator, it is easy to so control its passage that even dehydration and subsequent incineration are effected. Therefore, after the apparatus is once put in operation less heat is required at the burner end than would otherwise be required, thereby preventing fusing of the sand, so that as the sand leaves an incinerator, it may be immediately mixed with more sludge and returned to another incinerator, and a continuous hot sand cycle is provided. Another advantage is that as the sludge is subjected to the heat, it will first give off its moisture and later will be completely incinerated, the combustible gases given off during these stages being capable of developing sufficient B. t. u.'s. to very materially aid in the destruction of following sewage. Another advantage is that by using two or more incinerators, one set above the other, and the transferring of the hot sand from one incinerator to another, and then back to the first incinerator, a very simple and effective apparatus is provided capable of economic continuous operation. Another advantage is that the mixture of sand and sewage travels in a general longitudinal path, and that the burners project their flames in lines parallel with said path and at the terminal end thereof, so that the hottest zone in each incinerator is adjacent to its annular internal baffle.

Having thus explained the nature of the invention and described an operative manner of constructing and using the same, although without attempting to set forth all of the forms in which it may be made, or all of the forms of its use, what is claimed is:

1. A method of destroying sewage comprising intimately mixing sewage material with heated granular refractory material until the particles of refractory material are provided with coatings of colloidal sewage material, and completely destroying said coatings by subjecting the coated granular material to an incinerating temperature.

2. A method of destroying sewage comprising intimately mixing sewage material with heated granular refractory material until the particles of refractory material are provided with colloidal coatings of said sewage material, and dehydrating and subsequently completely destroying said

coatings by subjecting the coated granular material to a gradually increasing temperature.

3. A method of destroying sewage comprising heating an inorganic high temperature-resistant material, intimately mixing sewage material with the heated inorganic material until the particles of said inorganic material are provided with coatings of said sewage material, and effecting complete destruction of said coatings by subjecting the coated material to an incinerating temperature while traveling through a heated space.

4. A method of destroying sewage comprising heating an inorganic high temperature-resistant material by causing it to travel through a heated space, intimately mixing sewage with said temperature-resistant material until the particles of the latter are provided with coatings of said sewage material, and completely destroying said coatings by causing the coated temperature-resistant material to be recycled through the same heating space, and maintaining said space at an incinerating temperature during such recycling.

5. A method of destroying sewage comprising heating a granular refractory material, intimately mixing said heated granular material with sewage material until the particles of granular material are provided with coatings of said sewage material, dehydrating said coatings by causing the coated material to pass through a heated space, and completely incinerating the dehydrated coatings by gradually increasing the temperature of said heated space as the granular material approaches the end of its travel through said space.

6. A method of destroying sewage comprising intimately mixing sewage sludge and a heated high temperature-resistant inorganic material until the particles of said inorganic material are provided with coatings of said sewage, effecting initial dehydration and complete incineration of said coatings by causing the coated material to travel toward a source of heat so as to increase the temperature applied to the coatings during travel of the temperature-resistant material through said heated zone.

7. A method of destroying sewage comprising intimately mixing heated granular refractory material with sewage material until the particles of the granular material are provided with coatings of said sewage material causing said coated material to travel through a heated zone, to effect dehydration of said coatings, and increasing the temperature of the heated zone as the coated material approaches the end of its travel so as to effect complete incineration of said coatings, and subjecting the coated material to a turbulent tumbling action during its travel through said heated zone.

8. The method of destroying sewage comprising causing heated granular refractory material to travel in succession through a plurality of heating zones, and then recycling the same through said zones, intimately mixing sewage material with said refractory material prior to its entrance into each heating zone during the recycling stage and in such manner as to provide the particles of refractory material with coatings of said sewage material, and effecting complete incineration of said coatings by the action of the incinerating temperature maintained in the respective heating zones during the travel of the coated particles therethrough.
